UNITED STATES PATENT OFFICE.

FREDERICK JACOB GRAF, OF NEW YORK, N. Y.

CAR-FENDER.

SPECIFICATION forming part of Letters Patent No. 561,163, dated June 2, 1896.

Application filed March 14, 1896. Serial No. 583,183. (No model.)

To all whom it may concern:

Be it known that I, FREDERICK JACOB GRAF, a citizen of the United States, and a resident of New York, in the county of New York and State of New York, have invented certain new and useful Improvements in Car-Fenders, of which the following is a specification, reference being had to the accompanying drawings, forming a part thereof, in which similar letters of reference indicate corresponding parts.

This invention relates to fenders or guards for tramway-cars; and the objects thereof are to provide a device of this class which is novel in construction and operation and which is mounted beneath the platform of the car or one of which may be mounted beneath each of the platforms of the car in such manner that it is retained beneath the platform normally, but may be projected, whenever necessary, by the driver or motorman, and which may also be automatically projected under certain conditions, and which is provided with means for drawing it back into its position beneath the platform of the car, and also with means whereby the motion of the car or the revolution of the wheels assists in the projection thereof; and with these and other objects in view the invention consists in the construction, combination, and arrangement of parts, hereinafter described and claimed.

The invention is fully disclosed in the following specification, of which the accompanying drawings form a part, in which—

Figure 1 is a side view of a car provided with my improved fender or guard; Fig. 2, a plan view of one of the platforms thereof; Fig. 3, a bottom plan view of the fender or guard, showing also one of the axles of the car, the platform of the car being removed and a portion of the fender or guard being broken away; Fig. 4, a longitudinal vertical section of a part of the construction shown in Fig. 3; Fig. 5, a partial section on the line 5 5 of Fig. 4; Fig. 6, a partial section on the line 6 6 of Fig. 5; Fig. 7, a plan view of the fender or guard detached from the car; Fig. 8, a side view thereof; Fig. 9, a side view of a lever which forms a part of the operative mechanism and which is mounted on the platform of the car; Fig. 10, a similar view of a shaft which also extends upwardly through the platform of the

car and constitutes a part of the operative mechanism, a portion of said operative mechanism being connected therewith; and Fig. 11 is a sectional detail of the construction shown in Fig. 10.

In the drawings forming part of this specification, A represents a tramway-car provided with my improved fender or guard, one of which is mounted between the platform at each end thereof, and said fenders or guards at each end thereof are inclosed or bordered in, as shown at a, and at one end said car fender or guard is shown projected at a², and said fender or guard is shown in plan and in side view in Figs. 7 and 8, and it consists of a frame composed of a rear end bar B, a central cross-bar b, a front end rod or bar b², the ends of which are curved backwardly and provided with a cross rod or bar b³, on which are mounted rollers b⁴, of rubber or similar material, and the front end bar b² may also be covered with rubber tubing or similar material, if desired, and the rear end bar B, the central cross-bar b, and the front or forward end bar b² are connected by parallel rods or bars b⁵, any desired number of which may be employed, but seven of which are shown in the drawings.

The central cross-bar b, strictly speaking, does not form a part of the fender or guard, but is rigidly secured to and forms a part of a frame which is suspended beneath the platform of the car and which constitutes a support for the fender or guard proper, and is mounted on each of the side bars b⁵ are strong spiral springs b⁶, one end of which bears upon the cross-bar b, and the other being provided with a bearing b⁷, secured to said side bars or rods b⁵, and secured to the five inner rods or bars b⁸, in front of the central cross-bar b, is a cross-head C, to which is secured, centrally thereof and longitudinally of the frame, a metal plate C², one end of which is secured to said cross-head and the other to the rear end cross-bar B, and the upper surface of said plate C² is provided with upwardly-directed transverse teeth C³, and I also employ two supplemental longitudinal rods or bars C⁴, which form a part of the fender-frame and which connect the cross-head C and the rear end cross-bar B and pass loosely through

the central cross-bar b , by which the fender or guard is supported and by which it is guided in its motion or operation, as hereinafter described, and it will also be understood that all of the longitudinal rods or bars b^5 pass loosely through the central cross-bar b and are free to slide therein, and the supplemental rods or bars C^4 , which connect the cross-head C with the rear end cross-bar B , are arranged below the other rods or bars b^5 , as clearly shown in Fig. 8, and the forward end of the fender or guard frame is provided with arms D , in which are mounted rollers d , which are adapted to rest upon the ground and support the end of the fender or guard when it is projected in front of the car, as hereinafter described.

The platform E of the car, one of which is provided at each end, as will be understood, is provided with a suitable frame, which is suspended therefrom and which comprises vertical hangers F , at each of the forward corners thereof, one of which is shown in Fig. 4, the lower ends of which are connected by a cross-bar F^2 and similar vertical hangers G at about the middle of the platform, the bottoms of which are connected by cross-bars or plates b , as shown in Fig. 4, and extending from the cross-bar b forward is a plate g , the forward end of which is secured to the cross-bar F^2 , as is also clearly shown in said figure, and said plate g is provided near said cross-bar F^2 with a slot g^2 , below which is mounted a plate-spring g^3 , the rear end of which is secured to the plate g and the forward end of which is provided with an upwardly-directed head or projection g^4 , and the rods or bars b^5 of the fender or guard frame are passed through the cross-bar F^2 at the forward end of the platform, as clearly shown in Fig. 4.

I also provide a vertically-movable frame H , which is shown in Fig. 5, and which is supported on the cross-bar b , and which consists of vertical side posts h , which are united at their upper ends by a cross-plate h^2 , and which connect with the cross-bar b by pins or bolts h^3 , which move in slots formed therein, and passing through the hangers G or mounted in vertical slots formed therein is a shaft h^4 , on which is mounted a sprocket-wheel h^5 , which is adapted to operate in connection with the teeth or sprockets C^3 on the plate C^2 , and connected with the upper end of the vertically-movable sprocket-wheel frame is a belt, cord, or chain K , which passes over a pulley K^2 , which extends forward and connects with an arm k of a transverse shaft k^2 , which is provided also with another arm k^3 , to which is secured a cord or chain k^4 , which passes over a pulley k^5 and upwardly through the platform of the car and connects with a lever k^6 , which is suitably supported thereon, as shown in Figs. 2 and 9, and the transverse shaft k^2 is also provided with an arm k^7 , to which is secured a spring k^8 , one end of which is connected with the frame at k^9 , and a corresponding arm L is formed on or secured to said shaft

k^2 , which projects upwardly and backwardly and is provided with a rod L^2 .

It will be seen on an examination of Fig. 3 that two of the arms L and two of the rods L^2 are provided, and said rods pass through the hangers G , over the shaft h^4 , and through the vertical slots in which said shaft is mounted, and the operation thereof will be hereinafter described. It will also be seen that two of the arms k^7 and two of the springs k^8 are provided, one set being arranged at each end of the shaft k^2 , as shown in Fig. 3, and mounted on the shaft h^4 at opposite sides of the center thereof are two pulley-wheels M , which are shown in Fig. 3, and one of which is shown in Fig. 4, and mounted on each of said wheels is a chain, cord, or belt M^2 , each of which passes backwardly and around a wheel m , mounted on the adjacent axle of the car, and each of said chains, cords, or belts is crossed, as shown at m^2 in Fig. 4, and supported by hangers m^3 , adjacent to the axle, is a shaft m^4 , on which is mounted a wheel m^5 , on which is placed a chain, cord, or belt m^6 , one end of which is secured to the rear end of the fender or guard frame or to the cross-bar B thereof, as shown in Fig. 4. I also provide a vertical rod or shaft N , which passes through the forward end of the platform, and on which is mounted below the platform a wheel N^2 , on which is placed an endless chain, cord, or belt N^3 , which is passed around two separate pulleys at N^4 , adjacent to one side of the frame, and carried backwardly and passed over a pulley N^5 and then around a wheel N^6 on the shaft m^4 .

Mounted transversely at the front end of the frame by which the fender or guard is supported is a shaft O , provided with two central depending arms O^2 , one of which is shown in Fig. 4 and both of which are shown in dotted lines in Fig. 3, and the arms O^2 are united at O^3 and provided with an outwardly-directed plate O^4 , on which the lower end of the vertical shaft or rod N is adapted to operate, and the said shaft O is provided with a plurality of downwardly-directed pins O^5 , which are preferably six in number, and secured to the front of the frame is a transverse buffer O^7 , through which passes a plurality of buffer-bolts O^8 , provided with buttons or heads, and the inner ends of the buffer-bolts O^8 are adapted to bear upon the depending pins O^5 , and also upon the arms or pins O^2 , when driven inwardly, and secured to one of the depending pins O^3 is a spring O^9 , one end of which is secured to the frame, and which is adapted to draw the pins O^5 and O^2 outwardly after they have been driven in by the buffer-bolts or by the rod or shaft N , as hereinafter described.

Attached to the rear sides of the sides h of the vertically-movable sprocket-wheel frame H are outwardly-directed pins p , over which passes a chain or cord p^2 , the ends of which are secured to flat springs p^3 , which are provided with heads p^4 , which are adapted to operate in connection with the cross-bar b of

the fender-frame and to catch over the edge thereof to hold the fender in position when the same is projected, as hereinafter described.

5 Mounted on the vertically-movable rod or shaft N, above the platform, is a ratchet-wheel R, above which is a disk R², and said shaft passes through a plate R³, above which is placed a spring R⁴, which is adapted to force the ratchet-wheel R upwardly, and pivotally connected with the plate R³ at R⁴ is a segmental plate R⁵, to the upper side of which is rigidly secured a pawl R⁶, and the segmental plate R⁵ is provided near its free end and on its inner side with a semicircular cavity R⁷, and said plate is adapted to be pressed inwardly beneath the ratchet-wheel R and to hold the same in an elevated position in such manner that the shaft N cannot be depressed so that the lower end thereof will strike the 20 plate or arm O⁴ on the arms or pins O², and when said segmental plate is forced inwardly beneath the ratchet-wheel R the pawl R⁶ will operate in connection with the teeth on the ratchet-wheel, so as to prevent the movement 25 thereof, and passing through the pawl R⁶ and the segmental plate R⁵ is a screw-threaded pin or bolt R⁸, by means of which the segmental plate R⁵ may be secured in position beneath the ratchet-wheel or in position outside of said wheel in such manner that said ratchet-wheel and the shaft N may be depressed.

The upper end of the shaft or rod N is provided with a wheel S, which is held in place 35 by a screw-threaded cap S², and said wheel is provided with a central hub S³, which is screw-threaded, and by means of which it is mounted on the upper end of the shaft or rod N.

40 The spring p³, hereinbefore described, is secured to the cross-bar b of the fender-support, and when the fender or guard frame is withdrawn beneath the platform, as shown in Fig. 4, the springs b⁶ are compressed, and the head g⁴ of the spring g³ connects with the shaft U, on which the rollers d at the forward end of the fender or guard are mounted, and holds the same in its position beneath the platform against the operation of the spring b⁶, and the 45 operation will be readily understood from the foregoing description when taken in connection with the accompanying drawings and the following statement thereof.

If the car be in motion and a person or object be seen on the track and it is desired to project the fender or guard, the rod or shaft N is depressed by stepping on the disk R² or the ratchet-wheel R, if the disk is not employed, and said wheel is depressed, together 55 with the shaft, and the lower end thereof strikes the plate O⁴, which is mounted on the arms or pins O², which are secured to the shaft O, and said arms or pins are forced downwardly and backwardly, and operating upon 60 the spring g³ they release the head g⁴ thereof from its connection with the forward end of the fender or guard, and the latter is pro-

jected by the springs b⁶ a part of the distance through which it passes, and at the same time the shaft h⁴ and the sprocket-wheel h⁵ are revolved by the axle of the car by means of the wheels m, and the chains, cords, or belts M² and the sprocket-wheel h⁵, operating in connection with the sprocket-teeth C³ on the plate C², project the fender or guard to the full extent, as shown in Fig. 1.

70 It will be understood that the shaft h⁴ is always revolved by the axle on which the wheels m are mounted, and in order to withdraw the fender or guard beneath the platform the frame in which the sprocket-wheel h⁵ is mounted must be raised, and this is done by means of the lever k⁶ and the chain or cord k⁷, connected therewith, which operates upon the shaft k², the arm k, and the cord K, after 75 which the fender or guard may be withdrawn by turning the shaft or rod N, the operation of withdrawing the fender or guard beneath the platform being accomplished by the wheel N², which is mounted on said shaft, and the 80 endless chain, cord, or belt N³, which is passed around the pulleys N⁴, over the pulley N⁵, and around the wheel N⁶, on the shaft m⁴, on which is mounted the wheel m⁵, which carries the 85 chain, cord, or belt m⁶, which is secured to 90 the rear end of the fender or guard, as shown in Fig. 4.

If a person or object should be struck by the buffer-bolts O⁸, said buffer-bolts will strike the depending arms or pins O² and O³, and 100 the result of this operation will be exactly the same as that above described, the depending pins or arms O² operating to depress the spring g³ and release the head thereof from the forward end of the fender or guard, after which 105 said fender or guard would be projected, as hereinbefore described. It will therefore be observed that the fender or guard may be projected by the driver or motorman by means of the shaft or rod N, or that the same result 110 will be accomplished if a person or object be struck by the buffer-bolts O⁸, and in each of these operations the fender or guard is only projected a part of the distance through which 115 it moves, and the complete projection thereof is accomplished by means of the axle on which the wheels m are mounted and by the cords or belts M², which are connected with said 120 wheels and with the wheels M.

In the operation of raising the sprocket-wheel frame H, as hereinbefore described, the rods L² are first withdrawn, so that they will not project through the vertical slots in the side bars or plates G, in which the shaft h⁴ is mounted, and this is accomplished by the 125 lever k⁶ at the same time that the sprocket-wheel frame is raised, the cord or chain K being slack, so that the said rod will be withdrawn before the said cord or chain begins to raise the frame.

130 It will be understood that a person or object struck by the fender or guard will be received thereon or will fall thereon, and the passage of such person or object beneath the

car will thus be avoided, and the projection of the fender or guard, if a person or object should be struck by the buffer-bolts O^s , will also remove such person or object from the track, and in either event such person or object cannot pass beneath the car, and by means of this device, constructed as herein shown and described, the serious and sometimes fatal results which frequently follow the striking 10 of a person or object by a car when in motion will be prevented.

In practice one of these fenders or guards is connected with each platform of the car, and it is evident that changes in and modifications of the construction herein described may be made without departing from the spirit of my invention or sacrificing its advantages, and I reserve the right to make all such alterations therein and modifications 20 thereof as fairly come within the scope of the invention.

Having fully described my invention, I claim as new and desire to secure by Letters Patent—

25 1. The combination with the platform of a car, of a suitable supporting-frame suspended therefrom, and a sliding fender or guard which consists of a suitable frame which is adapted to slide in the bottom of the supporting-frame, and which is provided with springs by which it may be partially projected in front of the car, and with a plate, or bar provided with teeth or sprockets, and said frame being provided with a sprocket-wheel which is in 30 operative connection with one of the axles, and which is adapted to operate in connection with said teeth or sprockets, so as to assist in projecting the fender or guard, substantially as shown and described.

40 2. The combination with the platform of a car, of a suitable supporting-frame suspended therefrom, and a sliding fender or guard which consists of a suitable frame which is adapted to slide in the bottom of the supporting-frame, and which is provided with springs by which it may be partially projected in front of the car, and with a plate or bar provided with teeth or sprockets, and said frame being provided with a sprocket-wheel which is in 45 operative connection with one of the axles, and which is adapted to operate in connection with said teeth or sprockets, so as to assist in projecting the fender or guard, said fender or guard being composed of end pieces, and longitudinal rods or bars, which are passed through a cross-bar which forms a part of the supporting-frame, near the middle thereof, and also a similar cross-bar at the forward end of said frame, and the springs which are 55 adapted to project said fender or guard being mounted on a portion of said longitudinal rods or bars, forward of the middle cross-bar of the supporting-frame, substantially as shown and described.

65 3. The combination with the platform of a car of suitable hangers or supporting-frames, a fender or guard mounted in the bottom

thereof, and adapted to be projected in front of the car, springs connected with said fender or guard, and bearing upon a portion of the supporting-frame, and adapted to partially project the fender or guard, and means connected with the adjacent axle of the car, and with the fender or guard frame, for finishing the projection thereof, substantially as shown 75 and described.

4. The combination with the platform of a car, of suitable hangers or supporting-frames, a fender or guard mounted in the bottom thereof, and adapted to be projected in front of the car, springs connected with said fender or guard, and bearing upon a portion of the supporting-frame, and adapted to partially project the fender or guard, and means connected with the adjacent axle of the car, and with the fender or guard frame, for finishing 80 the projection thereof, said means consisting of a sprocket-wheel mounted in a vertically-movable frame and adapted to operate in connection with sprockets or teeth, formed on 85 the fender or guard frame, and said sprocket-wheel being in operative connection with the axle of the car, substantially as shown and described.

5. The combination with the platform of a car, of suitable hangers or supporting-frames, a fender or guard mounted in the bottom thereof, and adapted to be projected in front of the car, springs connected with said fender or guard, and bearing upon a portion of the supporting-frame, and adapted to partially project the fender or guard, and means connected with the adjacent axle of the car, and with the fender or guard frame, for finishing 90 the projection thereof, said means consisting of a sprocket-wheel mounted in a vertically-movable frame and adapted to operate in connection with sprockets or teeth, formed on 95 the fender or guard frame, and said sprocket-wheel being in operative connection with the axle of the car, substantially as shown and described.

6. The combination with the platform of a car, of suitable hangers or supporting-frames, a fender or guard mounted in the bottom thereof, and adapted to be projected in front of the car, springs connected with said fender or guard, and bearing upon a portion of the supporting-frame, and adapted to partially 100 project the fender or guard, and means connected with the adjacent axle of the car, and with the fender or guard frame, for finishing the projection thereof, said means consisting of a sprocket-wheel mounted in a vertically-movable frame, and adapted to operate in connection with sprockets or teeth, formed on 105 the fender or guard frame, and said sprocket-wheel being in operative connection with the axle of the car, and the frame or support being provided with a spring which is adapted to hold the fender or guard in its position beneath the platform, and a shaft which extends upwardly through the platform, and operative 110 devices by which the connection of the spring with the fender or guard is broken, substantially as shown and described.

7. The combination with the platform of a car, of suitable hangers or supporting-frames, a fender or guard mounted in the bottom thereof, and adapted to be projected in front of the car, springs connected with said fender or guard, and bearing upon a portion of the supporting-frame, and adapted to partially 115 project the fender or guard, and means connected with the adjacent axle of the car, and with the fender or guard frame, for finishing the projection thereof, said means consisting of a sprocket-wheel mounted in a vertically-movable frame, and adapted to operate in connection with sprockets or teeth, formed on 120 the fender or guard frame, and said sprocket-wheel being in operative connection with the 125 axle of the car, and the frame or support being provided with a spring which is adapted to hold the fender or guard in its position beneath the platform, and a shaft which extends upwardly through the platform, and operative 130 devices by which the connection of the spring with the fender or guard is broken, substantially as shown and described.

axle of the car, and the frame or support being provided with a spring which is adapted to hold the fender or guard in its position beneath the platform, and a shaft which extends upwardly through the platform, and operative device by which the connection of the spring with the fender or guard is broken, consisting of a shaft which is provided with depending arms or pins by which said spring is operated, and means connected with said vertical rod or shaft by which the fender or guard may be withdrawn beneath the platform, substantially as shown and described.

7. The combination with the platform of a car, of a suitable supporting-frame or hangers suspended therefrom, a fender or guard mounted in the lower part of said frame, and provided with springs by which it may be partially projected in front of the car, and devices connected with said fender or guard, and with said supporting-frame, and with the adjacent axle of the car, for completing the projection of the fender or guard, said supporting-frame being also provided at the forward end thereof, with a spring by which the fender or guard is retained beneath the platform, and means for operating said spring consisting of buffer-bolts which are movably mounted in a suitable buffer, and which are adapted to operate in connection with suitably-supported pins or arms which are adapted to bear upon said spring, substantially as shown and described.

8. The combination with the platform of a car, of a suitable support suspended therefrom, a fender or guard mounted therein, and adapted to be projected in front thereof, said fender or guard being provided with a plate having sprocket-teeth or projections formed thereon, and said support with a vertically-movable frame, in which is mounted a sprocket-wheel which is adapted to operate in connection with said sprocket-teeth, and the shaft of which is provided with other wheels which are in operative connection with one of the axles of the car, and means for operating said vertically-movable frame consisting of a lever supported above the platform of the car, and provided with a rope or chain which extends therethrough, and which passes over suitable pulleys in said frame, substantially as shown and described.

9. The combination with the platform of a car, of suitable supports suspended therefrom, a fender or guard mounted therein, and adapted to be projected by springs, supplemented by the forward motion of the car, means for retaining said frame beneath the platform, and devices for operating the same consisting of longitudinally-movable buffer-bolts which project in front of the car, substantially as shown and described.

10. The combination with the platform of a car, of suitable supports suspended therefrom, a fender or guard mounted therein, and adapted to be projected by springs, supplemented by the forward motion of the car, means for

retaining said frame beneath the platform, and devices for operating the same consisting of longitudinally-movable buffer-bolts which project in front of the car, and a vertical shaft or rod which extends through the platform, and which is adapted to be depressed so as to operate to release the fender or guard, and devices connected with said rod or shaft for withdrawing the fender or guard beneath the platform, substantially as shown and described.

11. The combination with the platform of a car, of a spring-operated fender or guard which is suitably supported beneath the same, and which is also provided with operating devices which are in connection with one of the axles of the car whereby it may be projected in front thereof, said platform being also provided with a vertically-movable shaft or rod, and means connected therewith, and with the platform for withdrawing the fender or guard beneath the platform, substantially as shown and described.

12. The combination with the platform of a car, of a spring-operated fender or guard which is suitably supported beneath the same, and which is also provided with operating devices which are in connection with one of the axles of the car whereby it may be projected in front thereof, said platform being also provided with a vertically-movable shaft or rod, and means connected therewith, and with the platform for withdrawing the fender or guard beneath the platform, substantially as shown and described.

13. The combination with the platform of a car, of a spring-operated fender or guard which is suitably supported beneath the same, and which is also provided with operating devices which are in connection with one of the axles of the car whereby it may be projected in front thereof, said platform being also provided with a vertically-movable shaft or rod, and means connected therewith, and with the platform for withdrawing the fender or guard beneath the platform, consisting of sprocket-teeth or projections formed on the fender or guard, a vertically-movable frame in which is mounted a sprocket-wheel which is adapted to operate in connection with said teeth or projections, substantially as shown and described.

14. The combination with the platform of a car, of a spring-operated fender or guard which is suitably supported beneath the same, and which is also provided with operating devices which are in connection with one of the axles of the car whereby it may be projected in front thereof, said platform being also provided with a vertically-movable shaft or rod,

and means connected therewith, and with the platform for withdrawing the fender or guard beneath the platform, consisting of sprocket-teeth or projections formed on the fender or 5 guard, a vertically-movable frame in which is mounted a sprocket-wheel which is adapted to operate in connection with said teeth or projections, and devices connected with the platform for operating said vertically-movable 10 frame, consisting of a lever, provided with a rope or chain which passes downwardly through said platform, and which is in connection with devices for releasing said vertically-movable frame, and for raising the 15 same, substantially as shown and described.

15. The combination with the platform of a car, of a fender or guard which is suitably suspended beneath the same, and which is adapted to be projected in front thereof, said 20 fender or guard being in operative connection with one of the axles of the car, in such manner that the movement of the axle is adapted to project the fender or guard in front of the car, said fender or guard being also provided 25 with springs which are adapted to assist in said projection, and with a spring by which it is retained in its position, beneath the platform, a suitably-supported shaft below said platform, provided with depending arms by 30 which said spring is operated, and a vertically-movable rod or shaft which extends through said platform, by which said pins or arms are operated, and means for locking said vertically-movable shaft or rod in a 35 raised position, consisting of a segmental plate which is mounted above the platform, and which is adapted to be swung beneath a ratchet-wheel supported thereon, and which is also provided with a pawl which is adapted 40 to operate in connection with said ratchet-wheel to prevent the revolution of said rod or shaft, substantially as shown and described.

16. The combination with the platform of a car, of a spring-operated fender or guard, 45 which is suitably supported beneath the same, and provided with means for retaining it in position, said fender or guard being in oper-

ative connection with one of the axles of the car, whereby it may be projected in front thereof, said fender or guard being adapted 50 to be released by means of longitudinally-movable buffer-bolts, and also by means of a vertically-movable shaft which passes through the platform thereof, and which is provided with a ratchet-wheel which is secured thereto, above the platform, and means for holding said shaft or rod in its raised position, consisting of a pivoted segmental plate which is adapted to be turned beneath the same and which is provided with a pawl 60 which is adapted to operate in connection with said ratchet-wheel, said vertically-movable shaft or rod being also provided with a wheel or pulley which is mounted thereon, beneath the platform and which is in connection with devices whereby the fender or guard may be withdrawn beneath the platform after it has been projected, substantially as shown and described.

17. The combination with the platform of a 70 car, of a spring-operated fender or guard which is suitably supported beneath the same, and which is adapted to be projected in front of the car, by means of operative devices connected with one of the axles thereof, a spring 75 by means of which the fender or guard is retained beneath the car, and another spring by means of which it is held in the projected position, and means for releasing the spring by which it is held beneath the car, in order 80 that it may be projected and devices for releasing the spring by which it is held in the projected position, and for withdrawing it beneath the platform, substantially as shown and described.

In testimony that I claim the foregoing as my invention I have signed my name, in presence of the subscribing witnesses, this 10th day of March, 1896.

FREDERICK JACOB GRAF.
